APPARATUS FOR CHARGING MELTING POTS OF TYPESETTING MACHINES

Andrew Olding Hebb, Newmarket, Ontario, and
William A. Whitney, Toronto, Ontario, Canada

Application February 5, 1944, Serial No. 521,202

7 Claims. (Cl. 22—80)

This invention relates more particularly to apparatus for charging a melting pot used on typesetting machines and our object is to devise simple apparatus of this nature which may be manufactured cheaply, which may be readily attached to existing machines, which will be automatic in operation, and which may be easily adjusted to vary the amount fed.

The invention is fully described and illustrated, by way of example, in the accompanying drawing in which

Figure 1 is a longitudinal section, partly in side elevation of our invention applied to a machine having a tiltable melting pot;

Figure 2 a plan view thereof; and

Figure 3 a cross-section on the line 3—3 in Figure 1.

In the drawing like numerals of reference indicate corresponding parts in the different figures.

1 is a tiltable melting pot of a typesetting machine of ordinary construction and operation. The pot is pivoted at 2 on the frame 3 of the machine and is oscillated thereon to discharge metal through the channel 4 to type forming molds, not shown. The means for imparting oscillatory movement to the pot is not shown since various means of doing so are well known in the art. The usual plunger 5 and cylinder or well 6 ensure the discharge of the metal to said molds in the usual manner. Means for feeding used slugs 7 automatically to the pot to replenish the supply of metal therein are provided and such means comprise a stationary guide 8 secured to any convenient part of the frame 3 of the typesetting machine. The guide has sides 9 which are secured together at each end in spaced relationship by cross bars 10. A rod 13 is slidably mounted in open bearings 12 formed in upwardly extending portions 11 so that the rod may be reciprocated therein relative to the guide and may be readily removed from the bearings. A follower 14 slidably mounted on the rod 13 carries a pawl 15 which engages serrations or ratchet teeth 16 formed on the rod whereby a movement in one direction of the rod will cause a corresponding movement of the follower.

To reduce lost motion between the rod and the follower a plurality of pawls 15 of different lengths are employed so that one of the pawls will be positioned for early engagement by one of the teeth 16.

Usually the used slugs 7 are carried in galley 17 each having an open end so that the slugs may be pushed therethrough to discharge them therefrom. The guide 8 is adapted to receive

a galley 17 and is provided with a set screw 18 to secure the galley in position. The follower 14 engages the slugs 7 at a point remote from the open end of the galley and is provided with a cramping member 19 for cramping engagement with the bottom of the galley to lock the follower from return movement when the rod 13 is returned to its initial position. Thus the rod imparts an intermittent movement in the feeding direction only to the follower. Moreover, the teeth 16 extend along the rod 13 to a point whereby the follower is intermittently moved only a sufficient distance to discharge all the slugs in the galley. When this point is reached, the follower may actuate a signal to notify the operator.

The pot 1 is provided with a shoulder 20 which may be on a bracket 32 secured to and extending upwardly from the top of the pot as shown in the drawing. The shoulder 20 is adapted, when the pot is tilted to discharge a portion of its contents, to engage a detent, or a hook 21 pivotally connected with a collar 22 which is secured to the end of the rod 13 and is longitudinally adjustable thereon. The stroke of the rod 13 and thus of the follower 14 may be varied relative to that of the shoulder 20 by shifting the collar 22 and thus the detent 21 relative to the shoulder whereby the lost motion may be varied. The rod 13 may be returned to its initial position by any suitable means such as one or more springs 23 secured to the rod and to any suitable stationary part such as the adjacent upwardly extending portions 11 of the guide 8. Any suitable stop means may be provided to limit the return movement of the rod to maintain the desired setting of the detent 21 relative to the shoulder 20 on the next tilting action of the pot 1. Such stop means may comprise a sleeve 33 adjustably secured to the rod 13 for engaging the said portions 11.

To stop the operation of the feeding means, the drive connection 20, 21 between the pot 1 and rod 13 may be automatically disconnected. The detent 21 carries a shoe or an anti-friction roller 24 which normally runs on a surface 25, suitably secured to or formed on the bracket 32 behind the shoulder 20. A lever 26 pivoted at 27 at the end of the surface 25 has one end pivotally connected with the spindle 28 of a float 29. The spindle 28 is slidably in a bearing 30 secured to said pot. When the level of the metal in the pot rises or lowers the float will lift and fall thus rocking the lever. The free end of the lever 26 is inclined at 31 and normally the inclined end

31 is positioned above the roller 24. However, when the metal in the pot reaches a predetermined level the float 29 will rise to swing the inclined end 31 into the path of the roller 24 and cause it to run up the incline 31 and along the lever 26. The detent 21 is thus moved to an inoperative position relative to the shoulder 20. The rod 13 and the follower 14 are thus not moved whereby additional slugs will not be fed to the pot 1 until the level of the metal therein drops sufficiently to cause the lever 26 to be moved out of the path of the roller 24. When this occurs the feeding means will again resume its function.

What we claim as our invention is:

1. Apparatus for charging a melting pot of a typesetting machine comprising a movable melting pot; means for carrying charging material and for discharging it into the pot; means for feeding the material from the carrier into the pot comprising a reciprocating rod operable by the movable pot; a follower slidable on the rod and having a one-way drive connection therewith for advancing the material towards the pot on each forward movement of the rod; and means for retaining the follower in its advanced position at the end of each stroke.

2. Apparatus for charging a melting pot of a typesetting machine comprising a movable melting pot; means for carrying charging material and for discharging it into the pot; means for feeding the material from the carrier into the pot comprising a reciprocating rod operable by the movable pot in one direction; a follower slidable on the rod and having a one-way drive connection therewith for advancing the material towards the pot on each forward movement of the rod; means for returning the rod; and means carried by the follower having a cramping engagement with the carrier to resist movement with the rod during its return stroke.

3. Apparatus for charging a melting pot of a typesetting machine comprising a movable melting pot; a guide on said machine, a galley having an open end for directing used slugs from the galley into the pot, the galley being carried by the guide; bearings carried by the guide; a reciprocating rod slidably and removably mounted in said bearings; a shoulder carried by said pot; a detent connected with the rod for engaging said shoulder to move the rod forward with the pot; means for returning the rod; a follower slidable on the rod and having a one-way drive connection therewith for advancing the slugs towards the pot on each forward movement of the rod; and cramping means carried by the follower for engaging the galley to resist movement with the rod during its return stroke.

4. Apparatus for charging a melting pot of a typesetting machine comprising a movable melting pot; a guide on said machine; a galley having an open end for directing used slugs from the galley into the pot, the galley being carried by the guide, bearings carried by the guide; a reciprocating rod slidably and removably mounted in said bearings; a shoulder carried by said pot; a detent engaged by said shoulder and adjustably connected with the rod to vary the move-

ment thereof relative to that of the shoulder during the movement of the pot in one direction; spring means connected with the rod and a stationary part to return the rod; a follower slidable on the rod and having a one-way drive connection therewith for advancing the slugs towards the pot on each forward movement of the rod; and cramping means carried by the follower for engaging the galley to resist movement with the rod during its return stroke.

5. Apparatus for charging a melting pot of a typesetting machine comprising a movable melting pot; a guide on said machine; a galley having an open end for directing used slugs from the galley into the pot, the galley being carried by the guide; bearings carried by said galley; a reciprocating rod slidably and removably mounted in said bearings; a shoulder carried by said pot; a detent connected with the rod for normally engaging said shoulder to move the rod in one direction with the pot; spring means connected with the rod and a stationary part to return the rod; a follower slidable on the rod and having a one-way drive connection therewith for advancing the slugs towards the pot on each forward movement of the rod; cramping means carried by the follower for engaging the galley to resist movement with the rod during its return stroke; a surface carried by the pot behind the shoulder; an anti-friction roller on the detent normally running on said surface; a lever having an inclined end; a float in the pot connected with the lever for positioning the inclined end thereof in the path of the roller when the level of the metal in the pot rises above a predetermined point so that the roller will run up the inclined end of the lever and along it to move the detent out of position for engagement with the shoulder.

6. Apparatus for charging a melting pot of a typesetting machine comprising a movable melting pot; means for carrying charging material and for discharging it into the pot; means for feeding the material from the carrier into the pot comprising a reciprocating rod having a one-way drive connection with the pot; a follower slidable on the rod and having a one-way drive connection therewith for advancing the material towards the pot as the rod is moved thereby; means for returning the rod to its initial position; and means for retaining the follower in its advanced position at the end of each stroke thereof.

7. Apparatus for charging a melting pot of a typesetting machine comprising a movable melting pot; means for carrying charging material and for discharging it into the pot; means for feeding the material from the carrier into the pot comprising a reciprocating rod having a disengageable drive connection with the pot; float controlled means for engaging and disengaging said drive connection; a follower slidable on the rod and having a one-way drive connection therewith for advancing the material towards the pot on each forward movement of the rod; and means for retaining the follower in its advanced position at the end of each stroke.
